UNITED STATES PATENT OFFICE.

ROBERT F. CARPENTER AND THOMAS F. ANDERSON, OF CLEVELAND, OHIO, ASSIGNEES,
BY MESNE ASSIGNMENTS, TO THE SANMETAL PRODUCTS COMPANY, OF CLEVE-
LAND, OHIO, A CORPORATION OF OHIO.

HINGE.

Application filed April 27, 1918. Serial No. 231,148.

To all whom it may concern:

Be it known that we, ROBERT F. CARPENTER and THOMAS F. ANDERSON, citizens of the United States, residing at Cleveland, 5 in the county of Cuyahoga and State of Ohio, have invented certain new and useful Improvements in Hinges, of which the following is a specification.

This invention relates to door hinges, and 10 more particularly to hinges for doors which it is desired should automatically swing when released to a definite position, either open or closed.

The invention has particular application 15 to doors for compartments of toilet rooms, or similar doors, which are usually provided with spring hinges to automatically return the door to normal closed or open position when released. These spring 20 hinges get out of order and require considerable repair and adjustment. It is also difficult to adjust such spring hinges to return the door to a definite position, such, for example, that it will properly align 25 with a companion door of a pair. If stops or bumpers are used to secure alinement of the doors in normal position then the doors are noisy and frequent replacement of the bumpers is necessary. Moreover, some 30 doors are so arranged as to be normally open while others are normally closed, and different sets of hinges are required for the two arrangements.

The object of the present invention is to 35 provide a door hinge which is of simple construction, which automatically returns the door to normal position, which requires no stops or bumpers for determining said position, which can be easily and readily 40 adjusted to define the normal position of the door so as to secure proper alinement of a pair of doors, and which hinge is also capable of adjustment to provide for either open or closed normal position of the doors.

45 Other objects of the invention are in part obvious and in part will appear more in detail hereinafter.

The invention comprises the door hinge hereinafter described and claimed.

50 In the drawings Fig. 1 is an elevation, partly in section, illustrating the hinge applied to a door; Fig. 2 is a front elevation of the hinge shown in Fig. 1; Fig. 3 is a

similar view, illustrating the cam member 55 reversed; Fig. 4 is a plan view of the stationary hinge member, as illustrated in Fig. 3; Fig. 5 is a perspective view of one member of the hinge clamp; and Fig. 6 is a rear elevation of a portion of the stationary hinge member. 60

In the embodiment shown in the drawings 1 represents the door frame or casing and 2 one of a pair of doors to be hinged to said casing, 2° representing a companion door of the pair. The door is provided at 65 its top with a suitable hinge connection to the casing. This connection can be of any desired type, the only requirement being that the door should be capable of vertical movement relative to the casing while turning about the hinge axis. As illustrated this hinge connection comprises a body 3 suitably attached to the top of the door and provided with an upwardly extending pin 4 entering and having vertical sliding movement in an opening in a socket member 5 attached to the door frame or casing. 70

The present invention is more particularly concerned with the hinge at the bottom of the door. This hinge comprises a 80 stationary member fastened to the casing and a movable member carried by the door. The movable member is in many respects similar to the corresponding movable member of the upper hinge. As illustrated, it 85 comprises a body portion 6 in the form of a plate suitably attached to the door, such as by countersinking the same therein, or, as shown, by providing said plate with ears 7 which embrace the door and are secured 90 thereto by screws 8. Attached to or forming a part of said plate is a depending pin 9, said plate also carrying two ears 10 between which is an antifriction member, such as a roller 11 turning on a pin 12 carried by said ears 10. The plane of rotation of said roller is perpendicular to the general plane of the door. 95

The stationary member of the hinge comprises a plate 13 constructed for attachment 100 to the door casing. Said plate may be directly secured to the casing, such as by countersinking the same therein, but is preferably provided on its rear face with a pair of vertically extending flanges 14 having 105 slotted lugs 15 to receive screws 16 threaded

into the plate 13. The slots of said lugs are horizontal so as to enable said flanges 14 to be adjusted horizontally along the plate 13 toward and from each other, to be thereby capable of embracing and being secured to door casings of different thickness. Preferably the lugs 15 on each flange are arranged in non-symmetrical relation to said flange, so that each flange, including its lugs, is identical with the other flange, and the lugs of the two flanges are in staggered relation when applied to the plate 13, as shown in Fig. 6.

Plate 13 carries a horizontal platform 17 on which is a vertically extending sleeve member or socket 18 to receive the pin 9. Surrounding the upper portion of said sleeve and supported upon said platform is an annular cam member 19. This cam member 20 has a central hub portion 20 which fits the sleeve 18 and is capable of rotatable adjustment about said sleeve and of being secured in any adjusted position thereon by a radially extending set screw 21. Member 25 also has an annularly extending cam portion in the form of a flange 21^a. Referring to Fig. 3 the upper surface 22 of this cam is convex, sloping downwardly in opposite directions from the higher middle portion toward two shoulders or abutments 23 near the rear of said member. At the higher central portion of said surface is a radially extending shallow seat 24. The lower surface 25 of said flange is concave 35 or of opposite slope to the upper surface. Cam surfaces 22 and 25 are complementary or have substantially corresponding configurations and the corresponding parts of these surfaces, that is, the parts directly 40 above and below each other, are substantially parallel, all as illustrated in Figs. 2 and 3.

When the cam member is assembled on the stationary platform, as shown in Fig. 1, 45 with its concave surface 25 uppermost, then the two portions of said surface slope downwardly toward the front of the hinge. Said surfaces 25 support the antifriction roller 11. Consequently the door 2 always tends to move by gravity to the position shown in Fig. 1 with the roller 11 at the bottom of the inclined surface 25. By loosening the set screw 21 the cam member may be rotatably adjusted so as to insure proper alignment of two doors of a pair when said doors 50 are in their normal closed position as shown.

The cam member may also be removed from the sleeve 18 and be ended or reversed, being re-applied to the sleeve 18 in the position shown in Fig. 3. In this position the door has two normal positions of rest, one at either side, in which positions roller 11 rests in contact with one or the other of the shoulders 23. If the door is moved 55 away from either of said positions roller 11

rides upwardly along the cam surface 22 and tends to return by gravity to its original position. The recess or seat 24 enables the door to be also held in an intermediate normal position, but slight movement of said door in one direction or the other away from said seat causes said door to move by gravity to normal position.

What we claim is:—

1. A hinge, comprising a stationary member, a co-operating movable member rotatable around a vertical axis relative thereto, and a cam member for causing said movable member to swing to normal position, said cam member being rotatably adjustable 75 around said axis to vary the normal position of the movable member.

2. A hinge, comprising a stationary member carrying a cam, and a co-operating member having turning movement relative thereto around an axis, said cam being rotatably adjustable around said axis.

3. A hinge, comprising a stationary member, a co-operating movable member, and a cam member therebetween for causing the 90 movable member to swing to normal position, said cam member having two sets of cam surfaces and being shiftable to two different positions to bring either of said sets of surfaces into action.

4. A hinge, comprising a stationary member, a co-operating movable member having turning motion relative thereto, and a cam between said members having upper and lower cam surfaces and adapted to be reversed to bring either of said surfaces into action.

5. A hinge, comprising a stationary member having a hollow tubular socket, a co-operating movable member having a pin entering said socket and adjustable around the axis thereof, and a cam for co-operation with said movable member, said cam surrounding said socket.

6. A hinge, comprising a stationary member having a hollow socket, a movable member having a pin entering said socket, and a cam surrounding said socket and having upper and lower cam surfaces and adapted to be reversed to bring either of said surfaces uppermost for cooperation with said movable member.

7. A hinge, comprising pivotally connected parts, a cam engaging member carried by one of said parts, and a reversible cam member carried by the other part and provided with complementary upper and lower cam surfaces of substantially the same configuration.

8. A hinge member for attachment to a 125 supporting part, said member including a base and two parallel duplicate plate members extending at right angles to said base member, connecting means between said base and plate members allowing adjustment 130

of said plate members toward and away from each other to embrace the supporting part.

9. A hinge, comprising pivotally connected parts, a cam engaging member carried by one of said parts, and a reversible cam member carried by the other part and having upper and lower cam surfaces, one of said members being rotatably adjustable about the pivotal axis.

10. A hinge, comprising pivotally connected parts, a cam member carried by one of said parts, and a cam engaging member carried by the other part, one of said members being adjustable with respect to the other.

11. A hinge, comprising pivotally connected parts, a cam member carried by one of said parts, and a cam engaging member

carried by the other part, one of said members being adjustable around the axis of said hinge.

12. A hinge, comprising pivotally connected parts, a cam engaging member carried by one of said parts, and a reversible cam member carried by the other part and provided with complementary upper and lower cam surfaces of substantially the same configuration, one of said surfaces being convex and the other concave, the convex surface being provided with seats at its opposite ends and near its center, and the concave surface with a seat near its center.

In testimony whereof we affix our signatures.

ROBERT F. CARPENTER.
THOMAS F. ANDERSON.

Certificate of Correction.

It is hereby certified that in Letters Patent No. 1,446,449, granted February 27, 1923, upon the application of Robert F. Carpenter and Thomas F. Anderson, of Cleveland, Ohio, for an improvement in "Hinges," an error appears in the printed specification requiring correction as follows: Page 2, lines 106 and 107, claim 5, strike out the words "and adjustable around the axis thereof" and insert the same to follow the word "socket" in line 109; and that the said Letters Patent should be read with this correction therein that the same may conform to the record of the case in the Patent Office.

Signed and sealed this 15th day of May, A. D., 1923.

[SEAL.]

KARL FENNING,
Acting Commissioner of Patents.
